UNITED STATES PATENT OFFICE.

CHARLES HARRINGTON PECK, OF PHILADELPHIA, PENNSYLVANIA.

TRAFFIC-GUIDE.

1,295,585.

Specification of Letters Patent. Patented Feb. 25, 1919.

Application filed August 3, 1915. Serial No. 43,494.

To all whom it may concern:

Be it known that I, CHARLES HARRINGTON PECK, a citizen of the United States, residing at Philadelphia, in the county of Philadelphia and State of Pennsylvania, have invented a new and useful Traffic-Guide, of which the following is a specification.

My invention relates to new and useful improvements in traffic guides, and has for its object to provide an audible signal in combination with a visible signal; the visible signal preferably comprising a plurality of signal arms or semaphores connected with suitable operating handles, whereby they may be raised or lowered, said handles also being connected with the audible signal, so that when certain of said handles are actuated, a signal of one character will be given and when the other handles are actuated, a signal of the other character will be given.

Another object of the invention is to provide in combination with a visible signal means for producing an audible signal.

A further object of the invention is to provide in combination with a street signaling device, a collapsible water proof booth.

With these ends in view, this invention consists in the detail of construction, a combination of elements hereinafter set forth, and then specifically designated by the claims.

In order that those skilled in the art to which this invention appertains, may understand how to make and use the same, I will describe its construction in detail, referring by numerals to the accompanying drawings forming part of this application in which—

Figure 1, is a side elevation of my improved traffic guide, the side curtains of the water proof booth being shown in section to clearly illustrate the interior construction.

Fig. 2, is an enlarged fragmentary isometric view of the upright or standard showing the audible signal actuating mechanism, and

Fig. 3, is an enlarged perspective view of the semaphore supporting means or head.

In carrying out my invention herein embodied, 2 represents an upright or supporting standard, having its lower end mounted in a stand or base 3, which is sufficient size and weight to prevent the device from tipping over while in use. On the upper end of the standard, is mounted a semaphore supporting member or head 4, having bifurcated lugs 5, in which are pivoted the signal

arms of semaphores 6, each having some suitable indication 7, such as the word, "Stop," and also other indication marks, such as the arrow head 8, the latter indicating the direction in which traffic may proceed.

The inner ends of these semaphores are provided with spectacles 9, of suitable colored material, such as red glass, arranged to co-act with a suitable lamp 10 centrally supported on the head 4.

The inner ends of the signaling arms of semaphores have attached thereto suitable connecting means 11, which preferably consists of closely coiled and practically inexpensive wire cables, and a covering of practically incompressible wire. The latter acts as a protective member for the inner wire. These connecting means run through the upright or supporting standard and into the control box 12, where they are each connected to an operating handle 13, 14, 15, and 16, said handles being pivoted into the control box and projecting through slots 17 in a control box cover 18 which is detachably secured to the box in any suitable and well known manner. The slots 17 at the lower ends are enlarged as at 19 to provide shoulders 20, so that the handles may be moved sidewise beneath said shoulders which will hold them in their lower position as will be obvious.

To each of the connecting members, 11, are attached supplementary connecting members 21, certain of which are connected with a main trip lever 22, while the other supplementary connecting members are attached to the secondary trip lever 23. The main trip lever 22 is pivoted at 24 to a suitable support 25, carried by the standard with its inner end normally held in a lower position by means of a spring 26. The main trip lever is also provided with two hammer actuating dogs 27, 28, adapted to co-operate with the hammer 29, for raising the same, said hammer being pivoted at 30 to the support 25 and normally pulled toward the gong or bell by means of a spring 31.

The main trip lever is further provided with an arm 32, having an offset 33, with which coacts the inner end of the secondary trip lever 23, pivoted at 34 to the support 25.

The support 25 is provided with a perforated lug or projection 35, to which is attached the audible signal device of bell 36. When either of the handles 15 or 16 is drawn

downward, the outer end of the main trip lever 22 will be likewise operated to cause both of the dogs 27 and 28 to actuate the bell hammer 29, causing said hammer to strike 5 the bell twice, but if either of the handles 13 or 14 is actuated, the secondary trip lever 23 will be moved to force the inner end of the main trip lever 22 upward through the medium of the arm 32, and this action will 10 cause only the dog 27 to actuate the hammer 29, causing the lever to strike the bell but once.

From the foregoing, it will be seen that when certain of the operating handles are 15 actuated, a signal of one character will be given while when the other operating handles are actuated, a signal of another character will be given.

Where the audible signal is used in combination with the visible signal, the pulling 20 down of any one of the operating handles will operate one of the semaphores, and when used at a street crossing where the street traffic moves at right angles, the operating 25 handles are actuated in pairs, so that each pair of semaphores in longitudinal alignment are operated in unison.

In order to prevent undue wear upon the semaphores, as they move from their raised 30 to their lowered positions, I provide suitable rubber buffers 37 at each of the bifurcated lugs, and also springs 38 attached to the head 4, and the inner ends of the semaphores to retard the downward movement of the semaphores.

The standard also carries an extension member 39, to which is secured an adjustable clamp 40 comprising a stationary member 41 and a hinged member 42 pivoted or hinged to 45 one end of the stationary member as at 43.

The other end of the stationary member has pivoted thereto a bolt 44 adapted to register with the slot 45 in a free end of the hinged member 42, said free end being 50 turned back to form a hook 46. On the screw 44 is mounted a cross bar 47 attached to engage the inner portion of the hook 46, the parts being adjusted or drawn together and held in their adjustment by the thumb 55 nut 48, threaded on a screw 44. In this clamp is mounted the umbrella stick 49 provided with the ordinary umbrella frame 50 and cover 51, said cover being slit or divided at one side from its top center portion 60 to the outer edge thereof as at 52 forming two overlapping flaps which are provided with suitable fastening members 53, such as the well known glove or separable clasp. The joint made by these two overlapping flaps is protected by a pivoted protective flap 54 which may be fastened down in the same manner as described for the two overlapping flaps.

The slit in the cover of the umbrella is 65 necessary to permit said umbrella to be

raised with the supporting standard 2 in registration with said slit, and after the umbrella is raised, the overlapping flaps are buttoned as before described. The umbrella may be used for shading the eyes of the traffic officer when the sun is shining brightly and also to protect him against inclement weather, and in addition to the umbrella, a further protection is provided against very bad storms, as when rain or snow is being blown about by high winds which consists of water proof curtains 55, detachably secured to the edge of the umbrella cover along the inside surface thereof by suitable fastening means 53, similar to those described before, and these curtains may be provided with transparent windows 56, such as celluloid. If found desirable, a seat 57, may be attached to the standard, and this seat may be of any desirable construction, either stationary or adjustable.

The control box is also provided with suitable eyes 58 whereby the zone chains or ropes may be attached to the traffic guide and said control box is also provided with a suitable locking device 59 for locking all of the operating handles in their raised positions.

Of course, I do not wish to be limited to the exact details of construction as here shown, as these may be varied within the scope of the appended claims without departing from the spirit of my invention.

Having thus fully described my invention, what I claim as new and patentable is—

1. A traffic guide comprising a standard, 100 signaling devices supported by said standard, means for actuating said signals, a bell, and a combination of trip levers actuated by the signal actuating means for sounding a signal of one character at one time and a signal 105 of a different character at another time.

2. A traffic signal comprising a bell, a hammer therefor, a main trip lever provided with means for engaging the bell hammer to actuate the same twice in succession, a secondary trip lever coacting with the main trip lever to operate the latter to cause the bell hammer to be actuated once, and means for actuating said trip levers.

3. A traffic guide comprising a support, 115 signal arms carried thereby, means for moving said arms into and out of signal positions, a clamp carried by the support, an umbrella attached to said clamp, the cover of said umbrella having a slit therein for registration with the support; fastening means carried by the umbrella cover in the region of the slit whereby the parts may be detachably fastened together, and curtains provided with transparent windows detachably 120 secured to the edge of the umbrella.

4. A traffic guide comprising a base, a standard, a head, lugs thereon, semaphores pivoted to said lugs, means for retarding the downward movement of the semaphores and 125

rubber buffers for shock absorbing, incident to the fall of the semaphores.

5. A traffic guide comprising a standard, signaling devices supported by said standard, a control box carried by the standard, a cover therefor, said cover having vertical slots therein of greater width at their lower ends to produce shoulders, operating handles pivoted within the control box and projecting through the slots in the cover and means 10 passing through the standard for connecting the operating handles with the signaling devices.

6. A traffic guide comprising a standard, 15 signaling devices supported by said standard, a control box carried by the standard, a

cover therefor, said cover having vertical slots therein of greater width at their lower ends to produce shoulders, operating handles pivoted within the control box and projecting 20 through the holes in the cover, means passing through the standard for connecting the operating handles with the signaling devices, a gong provided with a hammer supported by the standard, two coacting trip levers for actuating the bell hammer to cause 25 it to sound signals of different characters and means for connecting said trip levers with certain of the connecting means between the signaling devices and the operating 30 handles.

CHARLES HARRINGTON PECK.
